UNITED STATES PATENT OFFICE.

MATHIAS J. WEBER, OF CHICAGO, ILLINOIS, ASSIGNOR TO CONTINENTAL SCALE WORKS, OF CHICAGO, ILLINOIS, A CORPORATION OF ILLINOIS.

DESIGN FOR A WEIGHING-SCALE BEAM.

Application filed October 22, 1923. Serial No. 7,564. Term of patent 14 years.

To all whom it may concern:

Be it known that I, MATHIAS J. WEBER, a citizen of the United States, residing at Chicago, in the county of Cook and State of Illinois, have invented a new, original, and ornamental Design for Weighing-Scale Beam, of which the following is a specification, reference being had to the accompanying drawing, forming a part thereof.

On the drawing:

Figure 1 is a side elevation of a weighing scale beam; and

Fig. 2 is a top plan view of the same, showing my new design.

I claim:

The ornamental design for a weighing-scale beam, as shown.

MATHIAS J. WEBER.
